CHARGE FORMING DEVICE

Fred E. Aseltine, Dayton, Ohio, assignor, by
mesne assignments, to General Motors Corpora-
tion, Detroit, Mich., a corporation of Dela-
ware

Application August 9, 1929, Serial No. 384,726

33 Claims. (Cl. 261—34)

This invention relates to charge forming de-
vices for internal combustion engines and more
particularly to devices of this character which
comprise a plurality of primary carburetors,
5 which deliver a primary mixture of fuel and air
to a plurality of secondary mixing chambers lo-
cated adjacent the engine intake ports and in
which the primary mixture is mixed with addi-
tional air under certain operating conditions.

10 A device of this character is described in the
co-pending application of Fred E. Aseltine, Wil-
ford H. Teeter, and Carl H. Kindl, Serial No.
288,683, filed June 27, 1928.

15 It is the principal object of the present inven-
tion to provide improved means for enriching the
mixture during the acceleration period. With
this object in view, the invention consists pri-
marily in the provision of means to supply addi-
tional fuel to the primary mixture passages, which
20 convey primary mixture from the primary car-
buretors to the secondary mixing chambers, and
simultaneously to the secondary air passage,
which supplies additional air to the said second-
ary mixing chambers to be mixed with the pri-
25 mary mixture, as above set forth.

25 Further objects and advantages of the present
invention will be apparent from the following de-
scription, reference being had to the accompan-
ying drawings, wherein a preferred form of the
embodiment of the present invention is clearly
shown.

In the drawings:

Fig. 1 is a vertical, longitudinal section through
30 a charge forming device constructed in accord-
ance with the present invention and the intake
port with which it is associated.

Figs. 2 and 3 are fragmentary, detail sections
35 on the lines 2—2, 3—3 of Fig. 1.

Fig. 4 is an elevation of a carburetor unit in
40 which a modified form of the invention is em-
bodied, certain parts being shown in section.

Fig. 5 is a fragmentary elevation showing the
throttle operating mechanism in detail.

Fig. 6 is a detailed section of the throttle oper-
45 ating mechanism.

The device disclosed comprises a main air
manifold 10, having three outlet branches, the
middle branch 12 being shown herein. Each of
50 these branches communicates with one of the
intake ports 14 of a multicylinder engine. The
outlet branches are each provided with an at-
taching flange 16 for securing the manifold to
the engine block in the usual manner, and a
55 flange 18 to which the carburetor unit is secured.

The carburetor unit comprises a main housing

20, having an attaching flange 22, adapted to be
secured to the flange 18 by screws 24. An air
inlet coupling 28 is secured in position to register
with an opening in the upper wall of the housing
20, in any suitable way and may be connected
5 with an air cleaner if desired. A casting 30, in
which the passages supplying fuel to the nozzles
are formed, is secured by screws to the lower wall
of housing 20, and a sheet metal fuel bowl 32 is
held tight against an annular shoulder 34 on the
10 housing 20 by any suitable means. Fuel is con-
ducted from a main source of supply to the fuel
bowl through a conduit (not shown) and the
flow of fuel to the bowl is controlled by a float 36,
operating in the usual manner to maintain a sub-
stantially constant level of fuel therein.

Fuel flows from the bowl 32 to a plurality of
primary fuel nozzles 38, one of which is located
in each of the primary mixing chambers 40, the
construction of which is briefly described herein-
after. The fuel conduit between the fuel bowl
20 and the nozzles comprises the vertical fuel pas-
sage 42 communicating at its upper end with the
horizontal fuel canal 44, which connects with
each of the nozzles 38 through an orifice 46. Fuel
25 is admitted from the fuel bowl to the passage 42
at all engine speeds, through a fixed metering
orifice 48 and at high speeds additional fuel is
admitted through an orifice 50 controlled by a
valve 52, operated in the manner set forth in the
30 above mentioned application. This operating
means forms no part of the present invention
and need not be described further herein.

Fuel is lifted from the fuel bowl through the
above described fuel passages and nozzles 38 to
35 the primary mixing chambers by the suction
therein. Opening movements of the throttle
cause a reduction in mixing chamber suction
which might permit the fuel column to drop suf-
ficiently to cause a temporary fuel starving of the
40 engine unless means are provided to prevent this
action. For this purpose a check valve 54 is pro-
vided in an enlarged chamber 56 at the junction
of the channels 42 and 44, and on reduction of
45 mixing chamber suction, seats on the bottom of
the chamber, preventing downward flow of fuel.

Each primary fuel nozzle is provided with a
main fuel outlet 58 in the top of the nozzle and
a secondary fuel outlet comprising two orifices
60 and 62 in the vertical wall of the nozzle near
50 the bottom of the mixing chamber. At relatively
high speeds, the mixing chamber suction is suffi-
cient to lift fuel from the main outlet as well
as from orifices 60 and 62. At idling, or low
55 speed operation under load, however, the suc-

tion is enough to lift fuel only to some point between the top of the nozzle and the orifices 60 and 62, fuel flowing from these orifices by the action of gravity under such operating conditions. Each nozzle is provided with a restricted fuel metering orifice 63. The primary mixing chambers comprise the enlarged anterior ends of the primary mixture passages 64, which are parallel to each other and close together, as indicated in Fig. 2. When the carburetor is attached to the manifold, these passages register with conduits which convey the primary mixture to the secondary mixing chambers, as fully disclosed in the application above referred to. Restrictions 66 separate the primary mixing chambers from the remainder of the mixture passages to reduce the velocity of flow past the fuel nozzles for the purpose fully set forth in the above mentioned copending application.

20 A single throttle valve 68, which extends across all the primary mixture passages, controls the flow therethrough and is provided with grooves 70, which register with said mixture passages. This throttle is operated in a manner hereinafter 25 more fully described. The middle primary mixture passage communicates with a tube 72 fixed in the manifold branch 12. This tube constitutes one of the primary mixture conduits above referred to and conveys the primary mixture to 30 the secondary mixing chamber located in the middle branch of the manifold.

Nearly all of the air entering the carburetor flows through the inlet coupling 28 and is controlled by the main air valve 74, normally held 35 against a seat 76 by a spring 78, received between the valve and a flange 80, projecting from a sleeve 82, slidably mounted on a stationary guide sleeve 84, fixed in the housing 20, and serving also as a guide for the stem 86 to which the air valve 40 is secured. When it is desired to choke the carburetor to facilitate starting of the engine, the flange 80 is adapted to be lifted by means not shown herein, but fully described in the above application, until the upper end of the sleeve 82 45 engages the air valve to hold it closed. Sufficient air to carry the starting fuel from the nozzles to the intake ports is admitted through an elongated slot 87, formed in a plate 88, secured to the housing 20, as shown in Fig. 1.

50 The valve 74 admits air to the air chamber 90, from which air flows to the primary passage through an orifice 92 in the bottom of the air chamber and to the secondary mixing chambers through a passage 94, which connects with the 55 inlet of the manifold 10. The flow of air through this passage is controlled by a manually operable throttle 96, secured to a shaft 98, rotatably mounted in the main housing and by a suction operated valve 100, secured to a shaft 102, also 60 rotatably mounted in the main housing.

While the means for operating the primary and secondary throttle valves is no part of the present invention, such mechanism is shown in Fig. 5 and is briefly described hereinafter for the 65 purpose of enabling a more ready understanding of the operation of the device in general. An operating arm 101 is secured to a spindle 103 projecting from one end of the primary throttle 67 outside the main housing 20, said operating arm 70 being provided with an orifice in the free end in which some suitable form of operating connection may be attached. This operating arm is connected by a suitable lost motion connection to an arm 105 secured by a split clamp or any 75 other suitable means to one end of the shaft 98,

outside the main housing. An operating link 107, forming part of the lost motion connection is pivotally connected to the operating arm 101, while a pin 109 projects from the arm 105 through a slot 111 in said link. A regulating screw 113 5 is threaded in lugs 115 projecting from the operating link and may be adjusted to regulate the length of the slot 111, the upper end of said screw forming the lower end of the slot. A tension spring 117 is connected at one end to the 10 upper end of the link and at the other end to the pin 109, said spring tending to hold the pin against the upper end of the slot 111. With both throttles closed the parts are in the position shown in Fig. 5 with the pin 109 in engagement with the 15 screw 113. As the arm 101 is rotated in a counter clockwise direction to open the primary throttle valve, the link moves downwardly until the upper end of the slot 111 strikes the pin 109 before the operating arm of the air throttle is 20 moved, to permit a certain amount of independent movement of the air throttle before the air throttle begins to open. Adjustment of the screw 113 is effective to vary the amount of this independent movement of the primary throttle, 25 but said screw is generally so adjusted that the primary throttle may move without accompanying movement of the air throttle until the engine speed corresponds to a vehicular speed of approximately 20 to 25 miles per hour on a level. 30

On opening of one or both of the throttle valves, the suction in the air chamber 90 is increased and the valve 74 is opened to admit additional air and increase the quantity of mixture supplied to the engine. The opening of this valve 35 is retarded to prevent fluttering of the valve and to restrict the admission of air so as to enrich the mixture to some extent whenever the throttles are opened. For this purpose a dashpot is provided comprising a cylinder 104 which receives fuel from the reservoir 32, and a piston 106, secured to the lower end of the valve stem 86 by any suitable means. A check valve is provided in the bottom of the dash pot cylinder, as shown in the above application, to admit fuel 40 thereto on closing movements of the valve and to prevent escape of fuel therefrom as the valve is opened. The specific construction of this dashpot is not material so far as this invention is concerned, and may be any conventional form 45 of liquid dashpot which will properly retard the opening of the air valve. 50

As hereinbefore stated, the valve 100 is opened by engine suction when the air throttle 96 is 55 opened. In earlier devices of this type such as that disclosed in the above mentioned copending application, a dashpot has been provided for the purpose of retarding the opening of the valve 100 whenever the air throttle 96 is opened. The purpose of this dashpot and its construction are 60 fully disclosed in the application referred to, but its function is briefly set forth here in order to facilitate a clearer understanding of the present invention. If the valve 100 were allowed to open freely, the air admitted through the passage 94 65 would reach the secondary mixing chambers before the increased quantity of primary mixture resulting from the opening of the throttle and the mixture formed in the secondary mixing chambers would, therefore, be too lean to properly operate the engine immediately following any opening of the throttle. By retarding the opening of the valve 100, the time required for the air supplied through passage 94 to reach the secondary mixing chambers is substantially that 70 75

required for the increased supply of primary mixture to reach said mixing chambers.

The use of the dashpot has not been altogether satisfactory for the reason that the retarding effect is not always just that desired, and it has been found that unless the dashpot is constructed within very narrow limits of accuracy difficulties arise. In other words the dashpot is too sensitive and production somewhat difficult for this reason. In a device constructed in accordance with the present invention, however, it has been found that the dashpot can be less accurately made without disturbing the functioning of the carburetor and the problems of manufacturing correspondingly simplified.

These results are accomplished by the provision of a pump operated on opening movements of the throttle and so constructed that it supplies fuel not only to the primary mixture passages as in the earlier application referred to, but also to the secondary air passage 94 during the acceleration period. To this end the dashpot cylinder 104, which operates as a retarding means for the main air valve, is also constructed to operate as a fuel pump and for this purpose a fuel delivery tube 108 is connected near the bottom of the cylinder 104, as shown in Fig. 1, and is connected at its upper end in a block 110, secured to the lower side of the main housing 30 within the fuel bowl and above the level of fuel therein. The tube 108 communicates at its outlet end with a channel 112 extending transversely of the block 110 and communicates directly with three vertical passages 114, each of which communicates with the vertical passage 116, formed in the bottom wall of the main housing, as indicated in Fig. 3. The passages 116 communicate with the primary mixture passages and supply fuel directly thereto on operation of the pump 40 in the manner fully described in the above mentioned copending application. A fuel passage 118, shown in dotted lines in Fig. 1, connects with the passage 112 and also connects with a vertical passage 120, bored in the block 110 and communicating with a similar passage 122 bored in the wall of the main housing and extending upwardly to the secondary air passage with which it connects to deliver fuel thereto, as shown in Fig. 1. Two air passages 124 are provided which 50 admit air to the fuel passage 112 to form an emulsion of fuel and air therein and to reduce the suction communicated to the passage 126 from the primary mixture passages sufficiently to prevent fuel being drawn upwardly from the cylinder 104 to the passage 126 by the engine suction in a manner fully described in the earlier application. It will be noted that the passage 120 is provided with a restriction at 126 to limit the supply of fuel forced by the pump to the air passage 94. This restriction may be of whatever size is desired to give the most satisfactory results.

It will be clear that on operation of the above described pump, fuel is simultaneously injected 65 into the primary mixture passages and the secondary air passage, the fuel delivery passages being of the desired size to supply the desired quantity of additional fuel at the points referred to. By injecting fuel into the air supplied to the secondary mixing chambers through the passage 94, the retardation of the opening of valve 100 need not be so accurately timed as in the earlier device, and since the air passing through the passage 94 is impregnated with fuel by the action 70 of the pump, the effect produced by such air

reaching the secondary mixing chambers before the increased quantity of primary mixture is not so marked as in said earlier device.

In the form of the invention disclosed in Fig. 4, the pump is operated by the primary throttle instead of the air valve. To this end an operating arm 130 is secured by a screw 132 to one end of the primary throttle and at its other end is pivotally connected to a piston rod 134 which operates the pump piston. The lower end of the rod projects into a tube 136 slidably mounted on the pump piston and provided with a closed lower end. A flange 138 is formed at the bottom of this tube and is slidable in a small cylinder 140 in the pump piston 142 and closed by a screw cap 144 as shown in Fig. 4. A spring 146 is received within the cylinder 140 and normally holds the tube in the position shown in the drawings with the flange 138 in engagement with the top of piston 142. The piston 142 is slidable in 20 the cylinder 148 and is normally held in its upper position by a spring 150 in the pump cylinder between the piston and the bottom of said cylinder. The piston rod is not connected to the tube 136, but merely engages the closed bottom 25 end of said tube to move the bottom downwardly on downward movement of the rod.

An orifice 152 in the cylinder wall connects with a fuel delivery passage 154 leading to a channel 156 identical with the channel 126 and 30 formed in a block 158 identical with the block 124. A check valve 160 is received in a valve cage 162 mounted in an enlargement 164 in the fuel delivery passage and prevents return of the column of fuel from the delivery passage to the pump 35 cylinder when the pump is not operating.

The operation of this pump should be obvious on inspection of the drawings. The arm 130 rocks downwardly on any opening movement of the throttle, depressing rod 134 and moving the 40 tube 136 downwardly. This compresses the spring 146 and puts the air in cylinder 140 under pressure, which is effective to move the pump piston downwardly as soon as the resistance of spring 150 is overcome which will be almost immediately after the downward movement of the piston rod begins. The mechanism disclosed thus forms a slightly yielding connection between the throttle and the pump piston by means of which jar on the parts during operation is avoided. 45 Downward movement of the piston 152 forces fuel through the delivery passage 154 and the passages in the block 158 to the primary mixing chambers and the secondary air passage in the manner set forth in describing the form shown 50 in Fig. 1.

The construction of fuel delivery passages from the channel 156 to the fuel outlets is just the same as in the device disclosed in Fig. 1 and the remainder of the carburetor, other than the specific 60 pump shown in Fig. 4 is also identical with that disclosed in Fig. 1. Therefore the specific description of such structures need not be repeated.

The secondary mixing chambers are identical 65 and each comprises a Venturi tube 142 positioned adjacent the outlet end of the primary mixture conduit. Each venturi is provided with an external rib 144, adapted to be clamped between the shoulders 146 and 148 on the manifold and 70 engine block respectively when the device is assembled. The Venturi tubes serve to accelerate the flow through the primary mixture conduits in the manner fully disclosed in the earlier application.

While the form of embodiment of the present invention as herein disclosed, constitutes a preferred form, it is to be understood that other forms might be adopted, all coming within the scope of the claims which follow.

5 What is claimed is as follows:

1. A charge forming device for internal combustion engines comprising a mixture passage, means for supplying fuel and air thereto, a secondary air passage supplying additional air, a throttle, and a pump operated on opening movements of the throttle to positively inject fuel into the mixture passage and the secondary air passage.
- 10 2. A charge forming device for internal combustion engines comprising a mixture passage, means for supplying fuel and air thereto, a secondary air passage supplying additional air to the mixture passage at a point relatively remote from the fuel supply, a throttle, and a pump operated by the throttle to positively inject fuel into the secondary air passage and the mixture passage.
- 15 3. A charge forming device for internal combustion engines comprising a mixture passage, means for supplying fuel and air thereto, a secondary air passage supplying additional air, a throttle, a manually operable valve in said secondary air passage, and means operative on opening movements of the throttle to supply fuel to said secondary air passage posterior to said valve.
- 20 4. A charge forming device for internal combustion engines comprising a mixture passage, means for supplying fuel and air thereto, a secondary air passage supplying additional air, a throttle, a valve in secondary air passage operable concurrently with the throttle and means operative on opening movements of the throttle to supply fuel to said secondary air passage posterior to said valve.
- 25 5. A charge forming device for internal combustion engines comprising a mixture passage, means for supplying fuel and air thereto, a secondary air passage supplying additional air, a throttle, an air valve in said secondary air passage, means for opening said valve after the throttle has made a predetermined opening movement, and means operable on all opening movements of the throttle to supply fuel to said secondary air passage anterior to said valve whereby any fuel supplied to the secondary air passage before the opening of said air valve will accumulate in said passage until the valve is opened.
- 30 6. A charge forming device for internal combustion engines comprising a mixture passage, means for supplying fuel and air thereto, a secondary air passage supplying additional air, a throttle, suction and manually operated valves in the secondary air passage and means operated on opening movements of the throttle for supplying fuel to the secondary air passage at a point between the two valves.
- 35 7. A charge forming device for internal combustion engines comprising a mixture passage, means for supplying fuel and air thereto, a secondary air passage supplying additional air, a throttle, a valve in the secondary air passage adapted to be opened as the throttle is opened and means operated on opening movements of the throttle to supply fuel to said secondary air passage posterior to said valve and to said mixture passage anterior to the throttle.
- 40 8. A charge forming device for internal com-

bustion engines comprising a mixture passage, means for supplying fuel and air thereto, a secondary air passage supplying additional air, a throttle, a valve in the secondary air passage adapted to be opened as the throttle is opened and a pump operated by the throttle for injecting fuel into the secondary air passage posterior to said valve and into the mixture passage anterior to the throttle.

9. A charge forming device for internal combustion engines comprising a primary mixture passage, means for supplying fuel and air thereto, a secondary mixing chamber into which the primary mixture passage is adapted to deliver a primary mixture of fuel and air, a primary throttle for regulating the flow through the primary mixture passage, a secondary air passage for supplying air to the secondary mixing chamber, and means operative on opening movements of the primary throttle to supply additional fuel to the primary mixture passage and to supply fuel to the secondary air passage.

10. A charge forming device for internal combustion engines comprising a primary mixture passage, means for supplying fuel and air thereto, a secondary mixing chamber into which the primary mixture passage is adapted to deliver a primary mixture of fuel and air, a primary throttle for regulating the flow through the primary mixture passage, a secondary air passage for supplying air to the secondary mixing chamber, and a pump operated on opening movements of the primary throttle to inject fuel into the secondary air passage and primary mixture passage.

11. A charge forming device for internal combustion engines comprising a primary mixture passage, means for supplying fuel and air thereto, a secondary mixing chamber into which the primary mixture passage is adapted to deliver a primary mixture of fuel and air, a primary throttle for regulating the flow through the primary mixture passage, a secondary air passage for supplying air to the secondary mixing chamber, and means operated on opening movements of the primary throttle to supply fuel to the secondary air passage and primary mixture passage.

12. A charge forming device for internal combustion engines comprising a primary mixture passage, means for supplying fuel and air thereto, a secondary mixing chamber into which the primary mixture passage is adapted to deliver a primary mixture of fuel and air, a primary throttle for regulating the flow through the primary mixture passage, a secondary air passage for supplying air to the secondary mixing chamber, a pump for supplying fuel to the secondary air passage and primary mixture passage and means connecting the pump to the primary throttle for operation therewith.

13. A charge forming device for internal combustion engines comprising a primary mixture passage, means for supplying fuel and air thereto, a secondary mixing chamber into which the primary mixture passage is adapted to deliver a primary mixture of fuel and air, a primary throttle for regulating the flow through the primary mixture passage, a secondary air passage for supplying air to the secondary mixing chamber, a valve in said secondary air passage adapted to be opened as the throttle is opened and means operated as the throttle is opened for supplying fuel to said secondary air passage posterior to said valve.

14. A charge forming device for internal combustion engines comprising a primary mixture

- passage, means for supplying fuel and air thereto, a secondary mixing chamber into which the primary mixture passage is adapted to deliver a primary mixture of fuel and air, a primary throttle for regulating the flow through the primary mixture passage, a secondary air passage for supplying air to the secondary mixing chamber, a valve in said secondary air passage adapted to be operated by the primary throttle and adapted to 5 be opened after said throttle has made a predetermined movement, and means operated on all opening movements of the throttle for supplying fuel to said secondary air passage.
15. A charge forming device for internal combustion engines comprising a plurality of secondary mixing chambers, a plurality of primary mixture passages adapted to deliver a mixture of fuel and air thereto, means for supplying fuel and air to said primary mixture passages, a primary 10 throttle regulating the flow through said mixture passages, a secondary air passage for supplying air to all of said secondary mixing chambers, and means operated as the primary throttle is opened for supplying fuel to the secondary air 20 passage.
25. A charge forming device for internal combustion engines comprising a plurality of secondary mixing chambers, a plurality of primary mixture passages adapted to deliver a mixture of fuel and air thereto, means for supplying fuel and air to said primary mixture passages, a primary 30 throttle regulating the flow through said mixture passages, a secondary air passage for supplying air to all of said secondary mixing chambers, and means operated as the primary throttle is opened for supplying fuel to the secondary air passage and to all the primary mixture passages.
35. A charge forming device for internal combustion engines comprising a plurality of secondary mixing chambers, a plurality of primary mixture passages adapted to deliver a mixture of fuel and air thereto, means for supplying fuel and air to said primary mixture passages, a primary 40 throttle regulating the flow through said mixture passages, a secondary air passage for supplying air to all of said secondary mixing chambers, a valve in the secondary air passage adapted to be opened as the primary throttle is opened and means operated by said throttle during its opening movements for supplying fuel to said secondary air passage posterior to said valve and to said mixture passages anterior to the throttle.
45. A charge forming device for internal combustion engines comprising a mixture passage, means for supplying fuel and air thereto, a secondary air passage supplying additional air, a throttle, a pump operated on opening movements of the throttle to inject fuel into the mixture passage and secondary air passage, a fuel delivery 50 passage leading from the pump to said mixture passage and secondary air passage, and means to admit air to said fuel delivery passage.
55. A charge forming device for internal combustion engines comprising a plurality of primary mixture passages adapted to deliver a primary mixture of fuel and air to a plurality of secondary mixing chambers, a secondary air passage for supplying air to said secondary mixing chambers, a fuel pump operative on opening movements of the throttle and having a fuel delivery passage leading to all of said primary mixture passages and the secondary air passage, and means for admitting air to said fuel delivery passage.
60. A charge forming device for internal combustion engines comprising a mixture passage, air and fuel inlets for supplying fuel and air thereto, a secondary mixing chamber located adjacent the engine intake ports, and relatively remote from the fuel inlet, into which 65
- means for supplying fuel and air thereto, a secondary air passage supplying additional air, a throttle, a valve in said secondary air passage, means connecting the valve with said throttle for operation thereby, and a pump also operated by the throttle for supplying fuel to both the primary mixture passage and secondary air passage during the acceleration period.
65. A charge forming device for internal combustion engines comprising a mixture passage, means for supplying fuel and air thereto, a secondary air passage supplying additional air, a throttle, a valve in said secondary air passage, means connecting the valve with said throttle for operation thereby, said means being so constructed that the valve is not opened until after a predetermined opening movement of the throttle, and a pump operated by the throttle for supplying fuel to both the primary mixture passage and secondary air passage during the acceleration period.
70. A charge forming device for internal combustion engines comprising a mixture passage, means for supplying fuel and air thereto, a secondary air passage having a valve therein for supplying additional air, a throttle, a main air valve for controlling the admission of air to both the mixture passage and secondary air passage, and means operated by the main air valve for supplying fuel to the mixture passage and secondary air passage during the acceleration period.
75. A charge forming device for internal combustion engines comprising a mixture passage, means for supplying fuel and air thereto, a throttle controlling the flow of fuel mixture, a secondary air passage, a valve in said secondary air passage adapted to be opened after a predetermined opening movement of the throttle, a main air valve controlling the admission of air to the mixture passage and secondary air passage, and means operated by said main air valve for supplying fuel to the mixture passage and secondary air passage on opening movements of the throttle.
80. A charge forming device for internal combustion engines comprising a primary mixture passage, air and fuel inlets for supplying fuel and air thereto, a secondary mixing chamber located adjacent the engine intake ports, and relatively remote from the fuel inlet, into which 85

the primary mixture passage delivers a primary mixture of fuel and air, a primary throttle for controlling the primary mixture passage, a secondary air passage for supplying air to the secondary mixing chamber, and means operative on opening movements of the throttle for supplying fuel to the mixture passage and secondary air passage.

27. A charge forming device for internal combustion engines comprising a primary mixture passage, air and fuel inlets for supplying fuel and air thereto, a secondary mixing chamber located adjacent the engine intake ports, and relatively remote from the fuel inlet, into which the primary mixture passage delivers a primary mixture of fuel and air, a primary throttle for controlling the primary mixture passage, a secondary air passage for supplying air to the secondary mixing chamber, and a pump operated by the primary throttle for injecting fuel into the mixture passage and secondary air passage on opening movements of said throttle.

28. A charge forming device for internal combustion engines comprising a primary mixture passage, air and fuel inlets for supplying fuel and air thereto, a secondary mixing chamber located adjacent the engine intake ports, and relatively remote from the fuel inlet, into which the primary mixture passage delivers a primary mixture of fuel and air, a primary throttle for controlling the primary mixture passage, a secondary air passage for supplying air to the secondary mixing chamber, a main air valve controlling admission of air to the mixture passage and secondary air passage, and means operated by said air valve for supplying fuel to the mixture passage and secondary air passage as the throttle is opened.

29. A charge forming device for internal combustion engines comprising a plurality of secondary mixing chambers located adjacent the engine intake ports, a plurality of primary mixture passages adapted to deliver a primary mixture of air and fuel thereto, fuel and air inlets therefor relatively remote from the secondary mixing chambers, a secondary air passage for supplying additional air to all the secondary mixing chambers, a primary throttle for regulating the flow of primary fuel mixture, an air valve controlling the admission of air to the secondary air passage and primary mixture passages, and means operated by the air valve for supplying fuel to said air and mixture passages as the throttle is opened.

30. A charge forming device for internal combustion engines comprising a main housing having a mixture passage and secondary air passage formed therein, fuel and air inlets for supplying fuel and air to said mixture passage, a throttle

regulating the flow of fuel mixture through said mixture passage, a fuel distributor block having a plurality of fuel passages formed therein, a fuel pump having a fuel delivery passage supplying fuel to the passages in said distributor block, and fuel passages formed in the main housing connecting the passages in said distributor block with the mixture passage and secondary air passage.

31. A charge forming device for internal combustion engines comprising a main housing having a mixture passage and secondary air passage formed therein, fuel and air inlets for supplying fuel and air to said mixture passage, a throttle regulating the flow of fuel mixture through said mixture passage, a fuel distributor block having a plurality of fuel passages formed therein, a fuel pump having a fuel delivery passage supplying fuel to the passages in said distributor block, fuel passages formed in the main housing connecting the fuel passages in the distributor block with the mixture passage and secondary air passage, and an air passage in said distributor block admitting air to the fuel passages formed therein.

32. A charge forming device for internal combustion engines comprising a main housing having a plurality of primary mixture passages and a single secondary air passage formed therein, fuel and air inlets for supplying fuel and air to said primary mixture passages, a primary throttle regulating the flow of fuel mixture through all of said primary mixture passages, a fuel distributor block having a plurality of fuel passages formed therein, a fuel pump having a fuel delivery passage supplying fuel to the passages in said distributor block, and fuel passages formed in the main housing connecting all of the primary mixture passages and the secondary air passage with the fuel passages in said distributor block.

33. In a carburetor, a secondary mixing chamber, a primary mixture passage adapted to deliver a primary mixture of fuel and air to said secondary mixing chamber, a primary throttle valve in said mixture passage for controlling the flow of mixture therethrough, a fuel reservoir, an acceleration device comprising a fuel chamber having a restricted connection to the fuel reservoir, an actuating member movable in consonance with throttle position, a fuel-displacing member in said chamber slidably related to the actuating member, resilient means transmitting the force of the actuating member to the fuel-displacing member, and means for delivering fuel from said acceleration device both to the primary mixture passage and the secondary mixing chamber.
